PENCIL FLASH LIGHT MAGNET

Nicola C. Plutino, Welland, Ontario, Canada

Application September 6, 1934, Serial No. 742,994

5 Claims. (Cl. 175—367)

The present invention relates to a small implement or tool having controlled magnetic properties for extracting from the eye, skin and the like small particles of iron, steel or other substances which may be attracted to a magnet, and has for a main object to provide a construction of flash-light body or casing and a magnet constructed and provided with a socket adapted for interchangeable mounting on the flash-light body 10 with the usual bulb or lamp so that the magnet may be operated by the dry cells and by the switch device of the flash-light body.

Another object of the present invention is to provide a flash-light body of long, slender or thin construction simulating a pencil or fountain pen and wherein the switch or circuit closer may be incorporated in a clip structure for holding the device frictionally to the clothing, such as in a pocket or the like and to provide a construction wherein the magnet may be quickly and easily interchanged with a light bulb when it is desired for use.

A further feature of the present invention is to provide a construction of magnet which may 25 carry points of various characters constituting pole pieces for the magnet and which may be of pointed rigid form, flexible or spring form to effect a wiping or brushing action when used, or which may be given various other shapes, configurations or constructions for carrying out the particular purposes of use.

The invention further has an object to provide a simplified construction of implement or device which may be economically manufactured and 35 which will not easily get out of order, and wherein the dry cells used may be of any commercial manufacture and may be quickly and easily interchanged or replenished in the usual manner at present employed in flash-light constructions.

40 With the foregoing and other objects in view, the invention will be more fully described hereinafter, and will be more particularly pointed out in the claims appended hereto.

In the drawing, wherein like symbols refer 45 to like or corresponding parts throughout the several views.

Figure 1 is a longitudinal section taken through a magnet device embodying the features of the present invention.

50 Figure 2 is a detail enlarged section taken longitudinally through the detachable magnet.

Figure 3 is a similar view showing a slight modification in the construction of the magnet wherein a flexible or wiping pole piece may be used, 55 and

Figure 4 is a detail sectional view taken through the flexible pole piece.

Referring now to the drawing 10 designates the body portion or casing of a flash-light which is provided with an insulating lining 11 extending substantially throughout the length of the casing 10. The casing is adapted to receive therein in any desired number of dry cells 12 providing a suitable source of electric energy for operation of the device. The cells 12 are of the usual construction having the exterior sheaths or casings of electric conduction material providing one pole of the cell and which are each provided with a central core or pole piece 13 projecting beyond one end of the cell for electrical contact with the sheath or casing of the next adjacent cell, or with the central contact portion of a lamp or the like, in the usual manner. The inner end of the casing 10 is closed by a plug 14 or the like of any suitable construction and which in the present instance is shown as threaded into position so that the plug 14 may be removed for interchange or replacement of the cells 12. In the present instance the plug 14 is of hollow construction and carries therein a tension spring 15 adapted to bear against a follower or disc 16 of preferably electric non-conducting material and which is adapted to bear under tension of the spring 15 against the bottom of the adjacent cell 12.

The outer end of the casing 10 has secured therein, in any suitable manner, a lamp socket 17 which is in electrical communication with the casing 10 and is adapted to receive the plug 18 of a detachable device, such as the magnet shown, 35 a lamp bulb or the like adapted to be used in the body casing 10. The plug 18 may be of the screw type as shown or of any other suitable construction commonly used for holding plugs detachably in sockets and the plug 18 is provided in the present instance with a central contact button or stud 19 adapted to register with the adjacent central pole piece 13 of the outermost cell 12.

For closing the circuit through the cells 12, plug 18, socket 17 and the casing 10, the latter is 45 provided with a metallic spring clip 20 secured to one side of the casing 10 exteriorly thereof and which is of sufficient size and suitably located for securing the casing 10 to the clothing, such as to the edge of a pocket by frictional engagement of 50 the free end of the clip 20 with the outer wall of the pocket for binding the latter firmly against the side of the casing 10. The free end of the clip 20 is provided with a head 21 which may be of ball or other suitable shape and which when 55

freed from the clothing may be depressed into an opening or slot 22 provided in the adjacent side of the casing 10 and the lining 11 so that the head 21 may be forced into electrical contact with the adjacent exposed sheath of the dry cell 12.

The plug magnet of this invention comprises a shell 23 which is mounted on the outer end of the plug 18 and carried as a part thereof, the shell 23 being of suitable non-magnetic material and which is of sufficient size to partially fit at its inner end in the outer enlarged end of the socket 17, although any other suitable construction may be given the parts for carrying out the specific purpose for which they are intended. The shell 13 houses a coil 24 providing the body of a magnet having a core rod 25 which is secured in the outer tapering end of the shell 23 and which terminates in a pole piece or point 26 of any suitable configuration, such as conical as shown. The pole piece 26 is located at the apex or outermost point of the magnet so that it may be applied in relatively small places and may be utilized for attracting relatively small particles of magnetizable material. The ends 27 and 28 of the coil 24 may be connected in any suitable manner to the outer shell of the plug 18 and to the central contact piece or button 19 respectively of the plug for closing the circuit through the coil 24 when the clip 20 is depressed.

In the modification shown in Figure 3, the core rod 29 projects through the outer end of the shell 23 and is threaded for the reception of a detachable nut 30 which carries a flexible or spring wiper finger 31 of suitable width and construction for wiping contact over the surface of the skin, or for other desired applications.

This wiper 31 constitutes a brush and may be given various other constructions than as hereinafter specifically shown. The nut 30 and the wiper 31 are of course of magnetic material so as to constitute a continuation of the pole rod 29 of the magnet.

In use the magnet is self-contained as the flash-light body carries the source of energy and the implement or device may be readily carried by a doctor when called to remove fragments of magnetizable material which may lodge in the eye or the skin, and where the patient is not accessible to the usual hospital implements or a source of current. The device may be used as an ordinary flash-light with the usual bulb in the socket 17, and when it is desired to convert it to a magnet it is only necessary to interchange the bulb or light of the flash-light with the magnet of this invention. In application the device is proportioned to fit the hand so that the point 26 or the wiper 31 may be applied to the skin or part of the body in which the metallic particles have lodged so that the application may be made at a desired point so as to obtain the full force and effect of the magnet for withdrawing the magnetizable particles.

It is apparent that the casing 10 may be used as a support or holder for various other devices or attachments which are capable of use in connection with a flash-light.

By use of the insulating lining 11 with the opening 22 in one side thereof, the exterior paper or other insulating coverings or wrappers now used on dry cells may be completely removed so that the sheath or outer pole of the dry cell will be protected by the insulating lining 11 and the exterior side of the adjacent dry cell 12 will be exposed through the opening 22 so that the

clip when compressed will make the proper electrical contact through the cell.

It is obvious that various changes and modifications may be made in the details of construction and design of the above specifically described embodiment of this invention without departing from the spirit thereof, such changes and modifications being restricted only by the scope of the following claims.

What is claimed is:—

1. A flash-light magnet comprising a flash-light body having the usual dry cells, circuit closer and lamp socket therein, and a coil magnet having a socket plug adapted for detachable engagement in the socket of the flash-light casing and provided with a pole piece at its outer end, said coil magnet adapted to be closed in circuit with the dry cells when the circuit closer is closed for energizing the pole piece.

2. A flash-light magnet comprising a casing having a bulb socket in one end and adapted to receive one or more dry cells therein, a circuit closer mounted on the casing for closing the circuit through said socket, and a coil magnet having a plug for detachably engaging in the socket in said circuit for energizing the coil, and a pole piece for the coil extending outwardly thereof and having a configuration for application in use to extract magnetic material from the body.

3. A flash-light magnet comprising a flash-light body having a socket in one end, a circuit closer at its outer side and means for supporting dry cells within the body portion, a non-magnetic shell having a plug at one end for detachable engagement in the socket, a coil mounted in said shell having its opposite ends connected to the plug for closing the coil in the circuit of the flash-light casing, and a pole rod extending through the coil and projecting from the outer end of the shell for application to the body for extracting magnetizable particles therefrom.

4. A flash-light magnet comprising a casing body adapted to carry dry cells and having a lamp socket therein and a circuit closer operable from its exterior, a non-magnetic shell having a plug at one end for detachable engagement in the socket for closing the plug in circuit with the flash-light body, a coil mounted in the shell and connected in circuit with the plug, a core rod in the shell for the coil projecting beyond the shell and externally threaded, a detachable cap mounted on the outer end of the core rod, and a wiper carried by said cap and constituting a continuation of the core rod.

5. A portable magnet comprising a metallic casing having a lamp socket at one end and a spring clip at its outer side with a head on the end of the clip, an insulating lining in the casing, said lining and casing having an opening in one side in register with the head of the clip for receiving the head therethrough when the clip is depressed, said casing and lining adapted to receive therein flash-light cells with the exterior insulating coverings removed therefrom, a magnet coil, a non-magnetic shell enclosing the coil and having a plug on one end connected to the coil for detachable engagement in the lamp socket of the casing, and a pole piece extending through the coil and through the outer end of the shell adapted to be magnetized when the circuit is closed through the clip for attracting magnetizable particles to the outer end of the pole piece.
